[57] CLAIM

The ornamental design for a post and rear supported bicycle saddle with rear extension, as shown and described.

DESCRIPTION

FIG. 1 is an upper perspective view of a post and rear supported bicycle saddle with rear extension, showing my new design;

FIG. 2 is a rear elevation view thereof;

FIG. 3 is a left side elevation view thereof, and being a mirror image of the right side elevation view;

FIG. 4 is a front elevation view thereof;

FIG. 5 is a bottom plan view thereof; and,

FIG. 6 is a top plan view thereof.

The broken lines shown in FIGS. 1-5 are for illustrative purposes only and form no part of the claimed design.
